CLAIM

(21) Appl. No.: **29/151,076**

The ornamental design for a garment combining body
armour and outer shell, as shown and described.

(22) Filed: **Nov. 16, 2001**

DESCRIPTION

(30) **Foreign Application Priority Data**

FIG. 1 is a front elevation view of a garment combining
body armour and outer shell, showing our new design, in
which the outer shell is partly open to reveal the body armor
inside;

May 21, 2001 (GB) 2101946

FIG. 2 is a front elevation view thereof in which the outer
is closed;

(51) LOC (7) Cl. **02-02**

FIG. 3 is a rear elevation view thereof;

(52) U.S. Cl. **D2/829**; D29/100

FIG. 4 is a detail view thereof showing a waist portion of the

(58) Field of Search D2/831, 828-830,

body armor and a bottom panel of the outer shell; and,

D2/829, 728, 750; 2/85, 102, 108; D29/100,
101.4

FIG. 5 is a detail view thereof showing a panel on a sleeve
of the outer shell.
